UNITED STATES PATENT OFFICE.

EARL C. MCKINNIE, OF CHICAGO, ILLINOIS, ASSIGNOR TO NATIONAL X-RAY REFLECTOR COMPANY, OF CHICAGO, ILLINOIS, A CORPORATION OF ILLINOIS.

ILLUMINATING APPLIANCE.

1,212,375.

Specification of Letters Patent.

Patented Jan. 16, 1917.

Application filed May 19, 1913. Serial No. 768,394. Renewed June 17, 1916. Serial No. 104,236.

To all whom it may concern:

Be it known that I, EARL C. MCKINNIE, citizen of the United States, residing at Chicago, in the county of Cook and State 5 of Illinois, have invented certain new and useful Improvements in Illuminating Appliances, of which the following is a specification.

This invention relates to improvements in 10 illuminating devices or fixtures of the type used in connection with indirect and semi-indirect systems of lighting.

The especial object of my present improvements is to provide a combined interior 15 electric lamp supporting fitting with a series of reflectors adapted to reflect the rays of light from the main lamps in an upwardly and outwardly direction, and a member which is adapted to transmit with more 20 or less diffusion, rays of light from one or more auxiliary lamps of low wattage, through the translucent walls of the member, while illuminating said member.

A further object of my invention is to 25 provide a translucent bowl so arranged in respect to the other elements of the fixture, as to conceal from observation from below, the interior fittings while permitting free 30 access to the latter and to the bowl for cleaning and repairing purposes.

A still further object of my improvements 35 is to provide a fixture of simple and economical construction that will properly support the translucent member without producing shadows within it which would detract from its ornamental appearance and decorative effects.

Having the foregoing and other objects 40 of general utility in view, I have produced the lighting fixture illustrated in preferred and modified forms in the accompanying drawings, in which:—

Figure 1 is a top plan or interior view 45 showing one half of a fixture constructed according to my invention; Fig. 2 is a view partly in elevation, and partly in section showing a preferred adaptation of my invention; Fig. 3 is a plan view of an interior lamp-supporting fitting especially adapted 50 for use in my fixture, and Fig. 4 is a view partly in elevation and partly in section, showing a modified adaptation of my invention.

Referring to the details of the drawing,

especially as shown in Figs. 1 and 2, the 55 reference numeral 5 represents a shallow bowl made of glass, porcelain, or any other suitable material having translucent properties and of any degree of external ornamentation.

The reference numeral 6 represents a collar or rim which may be made of metal, plaster, wood, fiber, or other suitable material, and of either plain or highly ornamental design. The rim 6 is formed with an 60 inwardly extending annular flange 6^a, and with an annular shoulder 6^b on its inner face. Secured to the inner side of the rim 6, are hook-shaped lugs 7^a which engage the lowermost links of the suspension-chains 7, 70 which depend from a suitable overhead fixture (not shown).

8 represents a central junction box having radial openings in its side walls in which are inserted conduit pipes 8^a, to the 75 outer ends of which are secured sockets 8^c, which support lamps 9 and opaque reflectors 10, the latter being arranged below the lamps and of a shape to reflect the light rays from the lamps, in an upwardly and outwardly direction.

To support the lighting unit or interior fitting, composed of the box 8, branch pipes 8^a, lamps 9 and reflectors 10, in proper relation to the bowl 5, I provide radially arranged metal arms 11, the inner ends of which are secured at 11^a to the under side of the box 8 and the outer ends 11^b hook over a ring 12 which is welded or soldered to the shoulder 6^b of the rim 6.

Depending from the center of the bottom of the box 8, is a lamp 9^a of low wattage, the function of which is to illuminate the bowl 5, the outwardly flaring perimeter of which rests upon and is supported by the edge of 95 the annular flange 6^a. Instead of using but one low wattage lamp to illuminate the bowl 5, I may adapt the style of interior fitting shown in Fig. 3, in which four such lamps, as 9^b, are secured to the outer ends of radial 100 pipes 8^b, which alternate the pipes 8^a which carry the main illuminating lamps 9. This form is desirable where it is desired to effect a high illumination of the bowl 5, and secure a general illumination from the diffused 105 rays transmitted thereby.

In Fig. 4, the interior fitting corresponds with that shown in Fig. 2, except that a sus-

pension member consisting of a stem 16 having fork-shaped upwardly extending arms 16^a is secured to the socket of the lamp 9 as at 16^c, and the lower portion of the stem is 5 threaded as at 16^a and provided with an ornamental nut 17. The threaded portion 16^a of the stem passes through a hole 13^a in the bottom of the bowl 13, and the nut 17 is screwed up until it engages the under side 10 of the bowl, thus concealing the hole 13^a. By properly adjusting the nut 17, the peripheral edge of the bowl 13 will be forced up against the horizontal flange 14^a of the rim 14, thus effecting a close joint between 15 the latter and the bowl.

To remove the bowl for cleaning, it is only necessary to unscrew the nut 17. The chains 15 and hooks 15^a correspond with the similar members 7, 7^a, shown in Fig. 2. It 20 will be understood that the interior fittings referred to will be suitably wired and connected with a source of electric supply, such details not being shown, as their application is apparent and they form no part of my invention.

Having thus described my invention what I claim as new and desire to secure by Letters Patent, is:—

1. An illuminating appliance comprising 30 an annular rim having a continuous inwardly-extending flange at its lower peripheral edge; a translucent bowl supported from said flange; and a lighting unit arranged interiorly of said rim and bowl and 35 embodying a central junction box, lights connected thereto, and radial box-supporting arms having their inner ends detachably connected to the under side of said box and

their outer ends detachably connected with said flange. 40

2. An illuminating appliance comprising, an annular rim having a continuous inwardly-extending flange at its lower peripheral edge; a ring secured concentrically to said flange; a translucent bowl supported 45 from said flange; and a lighting unit arranged interiorly of said rim and bowl and embodying a central junction box, lights connected thereto and radial box supporting arms having their inner ends detachably 50 connected to the under side of said box and their outer ends provided with hooks which are detachably engaged with said ring.

3. An illuminating appliance comprising, an annular rim having a continuous inwardly-extending flange at its lower peripheral edge; a translucent bowl supported 55 from said flange; and a lighting unit arranged interiorly of said rim and bowl and embodying a central junction box, a plurality of horizontal lights and a depending light connected to said box, radial box supporting arms detachably connected at their inner ends to the under side of said box and at their outer ends to said flange, and a depending supporting element wherein the depending light is arranged detachably connected at its upper end to said box and at its lower end to the bottom of said bowl. 60

In testimony whereof I affix my signature in the presence of two witnesses:

EARL C. MCKINNIE.

Witnesses.

F. BENJAMIN,
M. A. MILORD.
